(57) **CLAIM**

The ornamental design for a IMA crane retrector, substantially as shown and described.

DESCRIPTION

FIG. 1 is an isometric view of a IMA crane retrector according to the invention showing our new design.
FIG. 2 is a front elevation view thereof,
FIG. 3 is a rear elevation view thereof,
FIG. 4 is a right elevation view thereof,
FIG. 5 is a left elevation view thereof,
FIG. 6 is a bottom plan view thereof; and,
FIG. 7 is a top plan view thereof.

1 Claim, 6 Drawing Sheets

FIG. 2

FIG. 3

FIG. 4

FIG. 5

FIG. 6**FIG. 7**
